UNITED STATES PATENT OFFICE.

FRANK R. DUNCAN, OF GHENT, KENTUCKY.

BOOT AND SHOE.

No. 854,571.

Specification of Letters Patent.

Patented May 21, 1907.

Application filed May 19, 1906. Serial No. 317,768.

To all whom it may concern:

Be it known that I, FRANK R. DUNCAN, a citizen of the United States, residing at Ghent, in the county of Carroll and State of Kentucky, have invented new and useful Improvements in Boots and Shoes, of which the following is a specification.

The invention relates to an improvement in boots and shoes and particularly to an attachment for overshoes which may be readily applied to or removed from the same and which in use will effectively secure the overshoe in place against possibility of accidental removal.

The main object of the invention is the production of an attachment of the class described which may be readily applied to and concealed within the overshoe, the construction providing for a removable connection between the attachment and overshoe and for the positive engagement of the attachment and shoe heel, whereby to prevent removal of the overshoe except at the will of the wearer.

The invention will be described in the following specification, reference being had particularly to the accompanying drawings, in which:—

Figure 1 is a view in section partly in elevation illustrating the application of my improved fastener, Fig. 2 is perspective of the fastener detached.

Referring particularly to the drawings my improved fastener comprises a base plate 1 designed to fit within the heel portion of the shoe, said plate approximating in outline the interior contour of said heel portion. Near the rear edge the base is provided with a heel plate 2 extending at approximately right angles to the base and designed to embrace the rear portion of the heel 3 of the shoe. The heel plate is provided at its forward terminals with upwardly projecting arms 4, which extend above said heel plate and are provided at their upper edges with clasp or engaging members 5, designed to receive and firmly though removably secure the upper edges of the overshoe above the heel portion thereof, as will be apparent.

The base 1 is centrally and longitudinally provided with an offset portion forming a groove way 6 in which is slidably mounted a bar 7. At the rear end the bar is bent upwardly about half the height of the heel plate and formed on its upper terminal with a forwardly projecting spur 8 designed to

register with and operate through an opening 9 formed in the heel plate. At the forward edge the base 1 is provided with lips 10 disposed on opposite sides of the guideway 6 and bent upwardly at an angle to the base plate, their free edges being rolled or otherwise formed to provide bearing sleeves 11, the formation being such as to dispose these sleeves wholly in advance of the plane of the lips. An operating rod 12 is mounted in the sleeves 11, being centrally formed with a crank portion 13, one end of said rod being provided with a handle or lever portion 14 projecting from the rod in a plane on the crank 13 and of a length to extend to or above the free upper edge of the overshoe when said lever is disposed in vertical or operative position.

The crank 13 is disposed between the bearing sleeves, that is in alignment with the guideway 6, the cross bar of said crank engaging an eye 15 formed at the forward end of the slide bar 7, said eye being preferably an integral extension of said rod suitably bent to embrace the cross bar of the crank.

A shield 16 is preferably secured to the base 1 and disposed to overlie the guideway 6, so that the slide bar may be freely moved in the guideway without interference from the heel of the shoe.

In use with the attachment secured to the overshoe by the clasps 5 engaging the edge thereof, and the base plate 1 resting upon the heel portion of the overshoe, the lever 14 is turned toward the front of the shoe, with the effect to rock the crank 13 in the rearward direction and thereby move the spur 8 to its rearward limit, that is slightly beyond the plane of the inner surface of the heel plate. The overshoe is now applied to the shoe in the usual manner, with the heel of the shoe resting snugly against the heel plate 2. The lever 14 is now returned to vertical or operative position, thereby forcing the spur 9 into the material of the heel, and serving to secure the overshoe against accidental removal. The overshoe may be readily removed by a disengagement of the spur 8 from the heel through suitable operation of the lever 14, it being noted that the concaved forward portion of the heel provides sufficient space for the necessary movement of the crank 13 in the disengaging operation.

The attachment as a whole is preferably made of light steel or similar material, whereby to avoid any noticeable increase in the

weight of the overshoe, while at the same time providing for continued reuse of the attachment without liability of breakage or excessive wear.

5. As the attachment is secured to the overshoe solely by the clasps 5 it is obvious that it may be quickly and conveniently initially applied or removed when desired.

The spur 8, slide bar 7 and crank 13 are 10 preferably so arranged that when in locking position said crank is disposed in vertical alinement with the bearing portions of the rod 12 within the sleeves 11, thereby avoiding any tendency to dislodge the connecting 15 medium through jar in the use of the overshoe.

By preference the distance between the lips 10 and the heel plate 2 is such as to 20 snugly receive the heel of the shoe, so that in use the independent movement or slip of the overshoe incident to the ordinary construction is prevented, whereby the life of the shoe is materially increased.

Having thus described the invention what 25 is claimed as new, is:—

1. An attachment for overshoes comprising a base plate designed to fit within the heel portion of the overshoe, a heel plate at the rear edge of said base plate, lips projecting from the forward edge of the base plate, a slide bar movable in the base plate, means 30 for operating said bar, and means carried by said bar to engage the heel of the shoe inserted in the overshoe.

35. 2. An attachment for overshoes comprising a base plate formed with a longitudinal guideway, a slide bar movable in said guideway, a heel plate projecting from the rear

edge of the base plate, a spur carried by the slide bar and operative through an opening 40 formed in the heel plate, a crank rod rotatably supported at the forward edge of the base plate, the crank portion of said rod being annularly connected with the slide bar, a lever for operating said rod, arms projecting 45 from the heel plate, and clasps carried by said arms to engage the free edge of the overshoe.

3. An attachment for overshoes comprising a base plate designed to fit within the heel portion of the overshoe, projections at the forward and rear edges of said plate to receive the heel of the shoe between them, a slide rod movable in the base plate, means carried by the forward projections and connected to said slide rod for operating the latter, and means carried by said rod and operative through the rear projection to engage the heel of the shoe. 55

4. An attachment for overshoes comprising a base plate designed to fit within the heel portion of the overshoe, a heel plate at the rear edge of said base plate, lips projecting from the forward edge of the base plate, a slide bar movable in the base plate, means 60 for operating said bar, and a spur carried by the slide bar and operable through the heel plate to engage the heel of the shoe inserted in the overshoe.

In testimony whereof, I affix my signature 70 in presence of two witnesses.

FRANK R. DUNCAN.
